DISPENSER

Paul F. La Vine, St. Paul, Minn.

Application March 22, 1957, Serial No. 647,906

4 Claims. (Cl. 224—16)

This invention relates to an improved dispenser for shell shaped objects. More particularly the improvement relates to a plastic elongated ring having different exterior diameters for mounting the ring in a holder and different interior diameters for holding the shells and frictionally sliding and pivotally rocking the shells to disengage them from the dispenser.

Metal frame rings have heretofore been utilized to dispense shot-gun shells from tubular styled shell vests. The metal rings are easily bent under pressure and rendered useless even though not worn out. This is a troublesome feature and requires careful care of the vest to avoid any accidental external pressure which would bend the rings. Further, the rings are comparatively expensive to make up and their cost of replacement is relatively high. Thus it will be recognized that there is some need for a relatively less expensive shell dispenser which is not subject to disfigurement and destruction upon bending under relative external forces and the internal forces of shell extraction.

Accordingly, it is an object of this invention or improvement to provide plastic relatively flexible shell dispensers.

Another object of this invention or improvement in shell dispensers is to provide a flexible plastic insert for shell vests through which the end of a shell projects for a release therefrom by rocking and pulling on the projecting end of the shell.

It is a further object of this invention or improvement in shell dispensers to provide for a flexible plastic elongated tube having different internal surface diameters, with the internal surface providing a wear resistant angularly sloping friction area and a relatively enlarged end area which permits rocking or tipping of an elongated shell to remove the same from its support and over the frictional angularly sloping area.

Further objects and advantages will be apparent from the following description of the accompanying drawings.

Figure 1 is a plan view of a dispenser embodied in this disclosure with the outline of the internal surfaces shown in dotted outline.

Figure 2 is a top plan view of the structure shown in Figure 1.

Figure 3 illustrates a modified specific shell dispenser for 12 gauge shot gun shells.

Figure 4 shows a partial vest portion with a series of shell retaining tubes with one tube section broken away to illustrate the position and operation of a shell dispenser shown in cross section.

The plastic dispenser tube is a molded polyethylene resin body A formed with an enlarged upper ring end 10 and an integral elongated tube portion 11 of lesser external diameter than the external diameter of the ring end 10. The plastic resin forming the tube body A is relatively hard but flexible material which will withstand pressures of heavy objects by flexing and then spring back into shape without breaking. A molded polyethylene provides a waxy relatively hard but flexible surface which

2

permits pulling pressure to draw objects retained by the tube to be pulled therefrom, in the manner as herein after described.

The hollow internal portion of the tube is shaped or molded of different diameters including a first inwardly sloping inlet end 12. The inlet end 12 provides a funnel like guide surface or mouth extending about the upper edge of ring 10 and merges or turns down into the inner surface of ring 10 and tube portion 11 forming a second 10 more sharply sloping surface 13. The surface 13, extending downwardly through an intermediate section of the length of tube portion 11, provides a gradually increasing integral body thickness which gradually decreases the internal diameter of the tube 11 throughout 15 its intermediate section extending downwardly from the ring 10 to somewhat over half the length of the tube 10, or to the end of the thickened section of the tube 11 at 14.

The lower internal end section 15 of the tube 11 is 20 hollowed out to a larger diameter than the internal decreasing diameter formed by the relatively thickened section of tube 11, produced by the sloping surface 13. This end section 15 is a sufficient diameter size to permit free ends of objects held within the tube by the slope 25 of surface 13 to be rocked or pivoted back and forth and around to work past the thickened intermediate portion of tube 11 at the point of its most reduced internal diameter.

In order to work or pull a rounded flanged object past 30 the small diameter end of slope 13, the walls of the tube 11 are provided with a series of elongated apertures 18, 19 and 20 extending from the top angularly inwardly sloping surface 13 down through the thickened portion of the ring body 11 into the bottom portion of tube A 35 substantially centrally of the enlarged diameter surface 15. The apertures 18, 19 and 20 permit the relative section of the thickened body portion 11 of tube A to flex slightly outwardly when pulling the somewhat enlarged and extending rounded rim edge of a shot gun shell, lip stick holder and like body through the dispenser tube A.

The modified dispenser structure B of Figure 3 is shown as measured for the relative exact diameter of holding and dispensing a 12-gauge shot gun shell by 45 about a 5-pound pull force when applied to the end thereof as will be explained with respect to Figure 4. In this arrangement the external diameter of mounting ring 24, which is .250 inch deep, measures 1.217 inches in diameter and the internal diameter at the inner top 50 or corner edge 25 measures .937 inch with the inward slope cut at an angle of 30°. This measurement permits the shell body 28 and its rim 29 to freely slide into the body of the dispenser B. The upper inner surface 30, from the edge 25 sloped inwardly at an angle of 4 55 degrees 12½ minutes for a distance extending a little over half the length of the dispenser tube B or .938 inch down to the point 31. At point 31 the internal diameter measures .808 inch and this provides a gradual differential in body thickness between the top edge 25 and 60 point 31 which catches the shell rim 29 about midway therebetween. The thickness of this body portion formed by slope 30 determines the amount of pull force necessary to extract the shell. In this case the pull force is about 5 pounds. By cutting the slope down to about 65 3 degrees a somewhat thinner body portion is provided lessening the pull to about 3 pounds for skeet and trap shooters who prefer the lighter pull force required to extract the shell from the dispenser.

In order to tip or rock the shell body 28, the lower 70 internal end of the dispenser tube B for .502 inch is provided with an inner peripheral surface 32 affording an inner diameter of .937 inch from the point 31 down

to the bottom or outlet edge 33 of the plastic dispenser tube B. The surface 30 and thickened body portion of dispenser B, at 31, or substantially midway of lower end of the tube surface 32, has an internal diameter of .937 inch. The apertures, as represented by 34, are spaced about the tube body in a manner similar to the apertures 18, 19 and 20.

Illustrative of an elongated hollow holding tube for dispensing tubular objects provided with an extended rim, there is shown in Figure 4 a segment of a shell vest C. The vest C is generally a cloth or canvas like body 35 provided with a series of shell retaining tubes 36, 37 and 38. Tube 38 being shown in broken section to illustrate a number of shell bodies 28 stacked in the tube. The base of each of the tubes are gathered, as by threads 39 and 40, to provide narrow openings through which only the lower ends of dispenser B will slide, with the enlarged, external diameter 10 of the ring 24 stopped or locked in the ends of the tubes 36, 37 and 38 by the threading as at 39 and 40. With this structure the plastic dispensers B permit the shell bodies 28 with their rims 29 to slide about half way through the dispenser so that the lower end of the shell body 28 can be grasped by the fingers and moved from side to side or rocked with a downward pulling pressure to force the rim 29 to slide over the flexing inner surface 30 of the dispenser tube B. As one shell is extracted another drops down with its end exposed in a similar manner ready for pulling from the dispenser tube B. While in this relatively specific illustration, I have more or less specifically described a dispenser for a 12-gauge shot gun shell it will be understood that similar larger and smaller dispensers A and B can be provided for larger and smaller shells or shell shaped bodies. Thus it will be understood that such changes can be made as will provide structures which fall within the scope of my claims.

I claim:

1. A shell dispenser insert for a metal rimmed shot gun shell, said insert consisting of an integral molded plastic body having an upper open end portion, an intermediate open portion and a lower open end portion, said body being formed as an elongated flexible plastic tube body having an integral enlarged external but narrow ring about said upper end portion adapted to secure the said flexible body to the end of an elongated holding tube for a plurality of said shells and the balance of the length of said elongated flexible tube body forming said intermediate portion and said lower end portion being of a uniformly lesser external diameter than the external diameter of said ring; the interior of said insert having at its upper open end a first inwardly wall sloping surface providing a shell guide, a second sloping wall surface on said intermediate body portion providing a substantially continuous wall of gradually increasing thickness against

which a shell rim is adapted to normally rest in said insert, the said second sloping being formed as an integral gradually thickened body portion of said insert which increases in cross-sectional thickness towards the lower open end of said insert and provides a gradually decreasing internal diameter body size extending throughout said intermediate open portion of said insert, and the balance of the tube body having an internal diameter at the said lower open end of a larger dimension than the internal diameter of said intermediate thickened wall portion of said insert, whereby when a shot gun shell is placed in said insert the lower end of the shell extends from the said lower open end portion of said insert in a manner to be grasped and when pulled upon, the metal rim of said shell flexes the circumferential diameter throughout the said intermediate thickened wall portion of said insert to allow the shell to be pulled therefrom.

2. The structure of claim 1 wherein the plastic body is provided with a series of elongated apertures extending from the said first inwardly sloping surface down into the said thickened body portion.

3. An improved shell dispenser insert for temporarily holding shell shaped objects having an enlargement thereon to be pulled therefrom, said insert consisting of a flexible plastic elongated tubular body having an upper end portion and a lower end portion of unitary molded flexible walls of different external and internal diameters, said upper end portion being formed with an enlarged external ring means for retaining said dispenser in a holding tube and providing an open mouth extending about the upper edge of said ring, said lower end portion formed of a flexible wall of a lesser external diameter than said ring and formed with an inwardly sloping surface extending downwardly through an intermediate section of the length of the said elongated tubular body to provide a gradually increasing integral body thickness which gradually decreases the internal diameter of the tube throughout its said intermediate section, a series of elongated apertures in spaced relation in said intermediate section, dividing said wall into integral spaced wall portions and an open lower end in said tube, whereby a shell shaped body is temporarily supported by said dispenser with the lower end thereof depending from said open lower end of said tubular body and is withdrawn therefrom by forcibly flexing the said thickened intermediate wall portions between said elongated apertures.

4. The structure of claim 3 wherein the plastic is polyethylene.
